UNITED STATES PATENT OFFICE.

ARTHUR A. JOHNSON, OF LYNDHURST, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,284,354.

Specification of Letters Patent. Patented Nov. 12, 1918.

Application filed July 7, 1917. Serial No. 178,173.

To all whom it may concern:

Be it known that I, ARTHUR A. JOHNSON, a citizen of the United States, residing in Lyndhurst, in the county of Bergen and State of New Jersey, have invented certain new and useful Improvements in Type-Writing Machines, of which the following is a specification.

This invention relates to an improvement in typewriting machines, and more particularly to a fan-fold attachment for making manifold copies continuously, using the same set of carbon sheets. This case is an improvement on my application, No. 176,488, filed June 23, 1917, and on the patent to Wernery and Smith, No. 1,182,055, dated March 16, 1915.

One of the objects of the invention is to provide improved means for enabling the same sheets of carbon to be used repeatedly with a number of successive sections of a fan-fold web, so that the sheet and carbon leaves will be always assembled relatively to each other in a pack. As one portion of each carbon sheet is worn out, a fresh portion may be drawn on to replace it. This avoids the necessity of frequently taking apart the assembled pack of interleaved carbon sheets and web.

For the purpose of facilitating the use of the continuous supply of carbon with the continuous fan-fold web, the plies of the web are threaded between a series of diagonal guides or warping bars, which direct the carbon sheets from the side into line with and between the layers of the fan-fold web. The supply rolls from which the carbon sheets are drawn are mounted on the table carriage on which the bars or guides are mounted. This table carriage moves forward with the advancing line-space rotation of the platen. Thus, the carbon sheets and their source of supply keep pace with the movement of the web. The carbon sheets are moved rearwardly relatively to the work-sheets, by pushing the table-carriage rearwardly. In doing this, the carbon sheets are not ordinarily withdrawn from their rolls, as only that portion which is between the folds of the work-sheet web is used. Locking or clamping means is provided for preventing the carbon webs from unwinding accidentally from their supply rolls, which

may be released when it is necessary to renew the carbon sheets between the folds of the work-sheet web.

The platen is raised, as more particularly described in the above-mentioned patent, for straightening out the bend in the assembled work web and carbon sheets, to enable the relative displacement or spacing between the same.

Other features and advantages will hereinafter appear.

In the accompanying drawings,

65

Figure 1 is a perspective view with the work-sheet web and carbon sheet removed to disclose the underlying structure.

Fig. 2 is a top plan view with the work-sheet web broken away to show the underlying structure.

Fig. 3 is a vertical section, taken from right to left, looking at the machine from the front, and shows the clamps for the carbon sheets as in action preventing the withdrawal of fresh carbon paper from the rolls.

75

Fig. 4 is a vertical section, taken at right angles to Fig. 3.

Fig. 5 is a detail view, similar to Fig. 3, except that the clamps for the carbon sheets are released, to enable the fresh supply of carbon sheets to be drawn from the rolls.

Fig. 6 is a diagrammatic perspective view, showing how the carbon sheets are interleaved between the folds of the work-sheet web.

A platen 1 is supported by an axle 2, which is pivotally mounted by means of a swinging frame 3 on the platen frame 4. The platen frame 4 is mounted on a carriage 5, which travels along rails 6 in the usual manner. The platen 1 may be rotated one or more line spaces by a knob 7, or line by line by a line-space lever 8. In either case, an axle 9 is rotated, which axle is in line with the platen axle 2, but not rigidly connected thereto. To connect the platen axle 2 with the knob axle 9, there is provided on the platen axle a gear 10 meshing with a broad pinion 11, which, in turn, meshes with a gear 12 of the knob axle 9, of substantially the same diameter as the gear 10. In this way, the rotation of the knob 7 and the movement of the line-space lever 8 are indirectly transmitted to the platen 1. This arrangement enables the platen 1 to be raised from its

normal typewriting position to such a position that the pack of work-sheet webs and carbon sheets may be straightened out, so that the carbon sheets can be readily slipped 5 along the work sheets for spacing purposes. To raise the platen in this way, there is provided a handle 13, which is normally locked in a typewriting position by a spring latch 14.

10 The work-sheet or web, indicated at 15, is in the present case of fan-fold type, and is shown to consist of five layers or folds which are connected in a continuous series at their side edges. This fan-fold web, as a whole, 15 is in a continuous strip which may or may not have printed forms thereon to be torn off successively as typewritten to form separate bills or letters. The web 15, in order to have the matter typewritten on the exposed 20 layers take on the under layers to form duplicate copies, must be interleaved with carbon sheets 16. There are four of these carbon sheets shown, one for each of the under layers of the fan-fold web. To direct the 25 carbon sheets 16 from a source of supply off to one side to a position between the layers or folds of the web 15, there are provided a series of triangular guide plates 17, which have diagonal guiding edges 18 arranged to 30 bend the carbon sheets at right angles. These guide plates 17 are supported laterally on opposite sides, so as to extend between the folds of the web 15 without interfering with the travel of the web. The guide plates 35 17 are mounted on a traveling table-carriage 19, which advances with the feeding of the work-sheet web and the carbon sheets in a line-space direction, so as to keep pace with the rotation of the platen. The table 19 also 40 keeps pace with the letter-space movements of the platen 1 by being mounted on an extension 20 carried by the typewriter carriage 5. This extension is supported by a roll 21 running on a rail 22, provided on a bracket 45 23, extending rearwardly from the typewriter frame. The mounting of the traveling table 19 may be of any suitable character, as by means of wheels 24, traveling in rails 25 provided by the extension 20. Although 50 the carbon sheets may be used repeatedly with a number of successive sections of the work-sheet web, in the course of time the portions of the carbon sheets used will be worn out. To replenish these worn-out portions 55 of the carbon sheets with fresh portions, the carbon paper is provided in the form of supply rolls 26, of which four are shown, one for each layer of carbon sheets required. These carbon rolls 26 are mounted 60 on the table 19, so that they will travel with the carbon sheets and with the work-sheet web during line-space movements of the platen, and during the withdrawal of the 65 table for spacing between the work-sheet web and the carbon sheets. The axles of the

rolls 26 are arranged parallel to the direction of travel of the table 19, so that the carbon sheets extend from these rolls to the guides 17, and then are warped to extend in the direction of travel of the table 19 and 70 also in the direction of the travel of the web 15. The rolls are arranged two on each side, the outer ones being slightly depressed below the inner ones, as illustrated in Fig. 3, so as to enable the lower carbon sheets to 75 clear the inner rolls. The rolls 26 may be detachably mounted in bearings 27, so that when all the carbon paper on them is used up, they can be replaced by fresh rolls. For this purpose, the bearings 27 are open bearings closed by springs 28, which engage the axles of the rolls 26.

In order that the carbon paper may not be drawn from the rolls 26 until it is desired to renew that portion of the carbon sheets 85 which is between the folds of the web, there are provided paper locks or clamps 29 and 30, one for each pair of carbon rolls 26. These clamps each comprise a stationary jaw 31 and a pivoted jaw 32. Normally, the pivoted jaws 32 are held in the position of Fig. 3 gripping the carbon-sheet strips between them. This is done by providing each of the swinging jaws 32 with a pin 33. These pins extend into cam slots 34 provided 95 in levers 35 and 36. The levers 35 and 36 are connected by a link 37, so as to move in unison, thereby closing or opening the clamps 29 and 30 in unison. The lever 35 is provided with a grip 38, whereby the levers 35 and 36 may be manipulated to open and close the clamps 29 and 30. The cam slots 34 are formed with end dwells (see Figs. 3 and 5) so that they will automatically swing the pivoted jaws 32 according to 100 the direction of movement of the levers 35 and 36, and the dwells will lock them in their open or closed position. In this way, the supply of carbon paper is not drawn on until needed, although the movement of the 110 work-sheet web relative to the carbon sheets would tend to draw the carbon paper from the roll.

The utility of the device will be readily understood when taken in connection with 115 the above description. Starting with the assembled pack of work-sheet web and carbon sheets, in position on the platen to be written on, the bill or other piece of work is typewritten line by line. The web and 120 carbon sheets will advance line by line with the line-space movements of the platen. The web and carbon sheets will draw the traveling table 19 along with them, and there will be no appreciable relative movement between the table and either the web or carbon sheets, the latter being locked by the clamps 29 and 30.

When a bill or other piece of work is completed, the platen 1 is raised by means of 130

the handle 13, so as to straighten out the bend in the assembled pack of paper. The table 19 can then be forced rearwardly by means of a handle 39, slipping the carbon 5 sheets rearwardly along the work-sheet web.

The table 19 can then be held or locked and the work-sheet web 15 drawn on further relatively to the carbon sheets if necessary, until the relative spacing between them is 10 obtained, which corresponds with the register of the carbon sheets with the next fresh portion of the work-sheet web. This may be determined in any suitable manner, as by bringing the leading edge of the work- 15 sheet web into engagement with an adjustable gage 40.

The platen 1 can then be returned to its typewriting position and rotated either by the knob 7 or the line-space lever 8, to bring 20 the initial line to be written on in register with the printing point of the typewriter. This will carry the table 19, the web 15 and the carbon sheets 16 along in unison. When the bottom edge of the 25 completed piece of work has come in register with a knife 41, the piece of work may be severed from the continuous strip of web. The new piece of work can be written line by line as before, and, when completed, a 30 relative spacing between the carbon sheets and the work-sheet web may be made and the operation repeated over and over again, thus obtaining duplicate copies of a number of successive pieces of work, such as 35 bills, in a continuous manner.

When the carbon sheets between the folds of the work-sheet web are released, they can be replaced by fresh sections of the carbon sheets. For this purpose, the clamps 29 40 and 30 are released, then the work-sheet web when drawn forward around the platen, instead of spacing relatively to the carbon sheets, if the table 19 is locked or held, will carry the carbon sheets along with itself, 45 drawing off fresh portions from the supply rolls 26. When a proper amount of carbon sheets has been drawn from the supply rolls 26, the clamps 29 and 30 can be brought into action again, so as to prevent more carbon 50 paper than is needed from being unrolled.

The used portion of the carbon sheet which is to be discarded will be cut off by the knife 41, when the particular bill or letter with which it is in register is severed from 55 the body of the web.

Variations may be resorted to within the scope of the invention, and portions of the improvements may be used without others.

Having thus described my invention, I

60 claim:

1. The combination with a platen arranged to support a work-sheet web interleaved with carbon sheets, of a carriage including said platen, a table slidable on and 65 traveling with the carriage and adapted to

effect a relative displacement between said sheets and the work-sheet web, and a source of supply of carbon sheets mounted on and traveling with said table, adapted to be drawn on for fresh sheet surface when that 70 in register and in use with the work-sheet web is worn.

2. The combination with a platen arranged to support a work-sheet web interleaved with carbon sheets, of a carriage including said platen, a table slidable on and traveling with the carriage and adapted to effect a relative displacement between said sheets and the work-sheet web and a source of supply of carbon sheets in excess of that 80 in register and in use with the work-sheet web mounted on and traveling with said table, and means for preventing a feeding of carbon sheets from the source of supply to the web. 85

3. The combination with a platen arranged to support a work-sheet web interleaved with carbon sheets, of a carriage including said platen, a table slidable on and traveling with the carriage and adapted to effect a relative displacement between said sheets and the work-sheet web and a source of supply of carbon sheets in excess of that 90 in register and in use with the work-sheet web mounted on and traveling with said table, means for preventing a feeding of carbon sheets from the source of supply to the web, and releasing means for said last-mentioned means to enable the replacement of worn out sections of said carbon sheets 95 by fresh portions of carbon sheets from said source of supply. 100

4. The combination with a platen arranged to support a work-sheet web interleaved with a carbon sheet, of a carriage including said platen, a bar-carriage for moving said carbon sheet forwardly and backwardly, guiding means forming part of said bar-carriage for directing the carbon sheet from points off to one side of the work-sheet web into the work-sheet web and in the direction of travel of the work-sheet web, and means for preventing the traveling movement of said guiding means from feeding said carbon sheet from the sides 110 115 into the web.

5. The combination with a platen arranged to support a work-sheet web interleaved with a carbon sheet, of clamping means for gripping said carbon sheet intermediate its ends and holding it independently of the web to prevent a traveling movement of the carbon sheet with the work-sheet web. 120

6. The combination with a platen, of a 125 table traveling toward and from the platen to coöperate with the platen in properly manipulating a manifold web with interleaved carbon sheets, guides for said carbon sheets on said table, and rolls for said car- 130

bon sheets mounted on said table on opposite sides of said guides so as to travel back and forth with said table.

7. The combination with a platen, of a table traveling toward and from said platen to aid in properly placing and manipulating a work-sheet web interleaved with carbon sheets, guides for directing the carbon sheets between the folds of said web, 10 said guides being mounted on said table to travel therewith, carbon sheet supply rolls mounted on said table on opposite sides of said guides so as to normally travel with said table, and clamps interposed between 15 said supply rolls and said guides for maintaining said carbon sheets stationary with respect to said table.

8. The combination with a platen, of a traveling table coöperating with said platen 20 to manipulate a work-sheet web interleaved with carbon sheets, said carbon sheets passing over said table at a plurality of transversely separated points, a plurality of clamps for preventing certain movements 25 of said carbon sheets, and a common closing and releasing mechanism for manipulating said clamps in unison.

9. The combination with a platen, of a traveling table coöperating with said platen 30 to assist in manipulating work and carbon sheets, fixed jaws on said table, swinging jaws coöperating with said fixed jaws to grip the carbon sheets, a cam lever for manipulating each of said swinging jaws, 35 and means to connect said levers to move in unison so as to close and open said jaws in unison.

10. The combination with a platen arranged to support a work-sheet web interleaved with a carbon sheet, of a guide for carrying said carbon sheet in from the side of the web and adapted to turn the carbon sheet parallel with the web, and a holding device for the carbon sheet along the edge 45 of the web, adapted to be released to enable a fresh carbon surface of said sheet to be fed into the web.

11. The combination with a typewriter carriage including a platen arranged to support a work-sheet web interleaved with a carbon sheet, of a guide for carrying said carbon sheet in from the side of the web and adapted to turn the carbon sheet parallel with the web, a holding device for the carbon sheet along the edge of the web, adapted to be released to enable a fresh carbon surface to be fed into the web, a table-carriage carrying said holding device and said guide, and a mounting for said table-carriage to enable it to be shifted on the typewriter carriage to reposition the carbon sheet relatively to the web.

12. The combination with a platen adapted to support a web, of guiding means 65 movable relatively to the platen for bring-

ing in a carbon sheet at the side of the web, and a movable device for advancing and withdrawing said sheet relatively to the web, while the carbon sheet is held to the guiding means.

13. The combination with a platen arranged to support a work-sheet web interleaved with a carbon sheet, of a guide for carrying said carbon sheet in from the side of the web and adapted to turn the carbon sheet parallel with the web, a holding device for the carbon sheet along the edge of the web, adapted to be released to enable a fresh carbon surface to be fed into the web, feed-rolls adapted to coöperate with said platen to feed the web forwardly, and a mounting for said platen adapted to swing it clear of the feed-rolls to enable the web to be straightened, to permit the relative shifting of the web and the carbon sheet.

14. The combination with a typewriter carriage including a platen arranged to support a work-sheet web interleaved with a carbon sheet, of a guide for carrying said carbon sheet in from the side of the web and adapted to turn the carbon sheet parallel with the web, a holding device for the carbon sheet along the edge of the web, adapted to be released to enable a fresh carbon surface to be fed into the web, a table-carriage carrying said holding device and said guide, a mounting for said table-carriage to enable it to be shifted on the typewriter carriage to reposition the carbon sheet relatively to the web, feed-rolls adapted to coöperate with said platen to feed the web forwardly, and a mounting for said platen adapted to swing it clear of the feed-rolls to enable the web to be straightened, to permit the relative shifting of the web and the carbon sheet.

15. The combination with a platen adapted to support a web, of guiding means movable relatively to the platen for bringing in a carbon sheet at the side of the web, a movable device for advancing and withdrawing said sheet relatively to the web, while the carbon sheet is held to the guiding means, feed-rolls adapted to coöperate with said platen to feed the web forwardly, and a mounting for said platen adapted to swing it clear of the feed-rolls to enable the web to be straightened, to permit the relative shifting of the web and the carbon sheet.

16. The combination with a platen arranged to support a work-sheet web interleaved with a carbon sheet, of a carriage including said platen, a bar-carriage for moving said carbon sheet forwardly and backwardly, guiding means forming part of said bar-carriage, for directing the carbon sheet from points off to one side of the work-sheet web into the work-sheet web and in the direction of travel of the work-sheet web, means for preventing the traveling move-

ment of said guiding means from feeding said carbon sheet from the sides of the web, feed-rolls adapted to coöperate with said platen to feed the web forwardly, and a 5 mounting for said platen adapted to swing it clear of the feed-rolls to enable the web to be straightened, to permit the relative shifting of the web and the carbon sheet.

17. The combination with a platen arranged to support a work-sheet web interleaved with a carbon sheet, of a carriage including said platen, a table slideable on and traveling with the carriage and adapted to effect a relative displacement between said 10 sheets and the work-sheet web, a source of supply of carbon sheets mounted on and traveling with said table, adapted to be drawn on for fresh sheet surface when that in register and in use with the work-sheet 15 web is worn, feed-rolls adapted to coöperate with said platen to feed the web forwardly, and a mounting for said platen adapted to 20

swing it clear of the feed-rolls to enable the web to be straightened, to permit the relative shifting of the web and the carbon sheet. 25

18. The combination with a platen arranged to support a work-sheet web interleaved with a carbon sheet long enough to furnish impression surfaces for a plurality of written forms, of a clamping device for 30 gripping said carbon sheet, so as to leave one form free for writing and hold another form in reserve, and adapted to hold the carbon sheet from being moved with the web, feed-rolls adapted to coöperate with said platen to 35 feed the web forwardly, and a mounting for said platen adapted to swing it clear of the feed-rolls to enable the web to be straightened, to permit the relative shifting of the web and the carbon sheet.

ARTHUR A. JOHNSON.
